UNITED STATES PATENT OFFICE.

JULES M. MARTON, OF NEW YORK, N. Y.

DESIGN FOR A JAR OR SIMILAR ARTICLE.

Application filed March 27, 1923. Serial No. 5,616. Term of patent 3½ years.

To all whom it may concern:

Be it known that I, JULES M. MARTON, a citizen of the United States, residing at New York city, N. Y., in the county of New York and State of New York, have invented a new, original, and ornamental Design for a Jar or Similar Article, of which the following is a specification, reference being had to the accompanying drawing, forming a part thereof.

The figure is a perspective view of a jar. The receptacle is an imitation of a volcano with flames at the top of its cone, said flames preferably being adapted to serve as a grip or handle for the stopper of the receptacle.

I claim:

The ornamental design for a jar or similar article, as shown.

JULES M. MARTON.
